VESTIBULE TRAP-DOOR ARRANGEMENT

Christian J. Beezhold, Chicago, Ill., assignor to
Pullman-Standard Car Manufacturing Company,
Chicago, Ill., a corporation of Delaware

Application May 4, 1946, Serial No. 667,287

18 Claims. (Cl. 105—430)

1

This invention relates to a trapdoor arrangement for the vestibules of railway passenger vehicles and has for its primary purpose the provision of a trapdoor which may readily be applied to the vehicle structure without the necessity of elaborate fitting operations.

The principal object of the invention comprises the provision of a trapdoor and mounting adapted for construction as a sub-assembly which may be installed as a unit in the step well of a vehicle at the erection location.

An important object of the invention is realized in the sub-assembled fabrication of the trapdoor with its relatively movable hinge mounting member constructed as an integrated part of the door for application to the platform structure of a vehicle with the door and comprising the means of attachment for the door.

Another object of the invention is accomplished in the provision of a trapdoor which may be conveniently and efficiently weatherstripped at all of the sides thereof forming joints with the platform leading to the interior of the vestibule so that the step well is completely sealed off from the vestibule.

The foregoing and other and important objects of the invention are attained by the construction and arrangement hereinafter described and illustrated in the accompanying drawings, in which:

Fig. 1 is a general perspective view of a railway car vestibule and platform area illustrating the trapdoor arrangement of this invention and showing the vestibule folding step assembly and connected trapdoor in their open positions with the steps operatively disposed and the trapdoor disposed vertically and releasably secured against the outer face of the open vestibule side door;

Fig. 2 also is a perspective view of the vestibule and platform area with the folding steps in operative position, but with the trapdoor disconnected and removed to a point above the level of the platform and disposed horizontally in vertical alignment with the step well opening showing the trapdoor with its attached hinge structure in position for application to the platform structure;

Fig. 3 is a plan view of the trapdoor to larger scale, showing the trapdoor in position over the step well closing the platform opening, and illustrating the hinge for attaching the door to the platform structure and permitting raising of the trapdoor to expose the steps;

Fig. 4 is a sectional view through the trap-

2

door and adjoining platform structure at the step well taken lengthwise of the door on the line 4—4 of Fig. 3 and showing the attached hinge member secured to a supporting angle member at the body end wall of the vehicle and also showing the manner of weatherstripping the trapdoor at its hinged and free edges;

Fig. 5 also is a sectional view through the trapdoor but taken transversely of the door on the line 5—5 of Fig. 3 through the adjoining platform structure at the inner weatherstripped side of the trap door and through the outer side threshold portion of the trapdoor with the vestibule side door and folding step assembly shown in their closed positions above and below the threshold with the former weatherstripped as indicated;

Fig. 6 is a fragmentary sectional view taken on the line 6—6 of Fig. 3 through the trapdoor hinge adjacent the threshold, showing the arrangement of one of the hinge pins about which the trapdoor rotates;

Fig. 7 is an outside elevational view showing fragmentary portions of the vestibule side door and folding steps in their closed positions with the outer threshold portion of the trapdoor shown therebetween and illustrating the weathersealed condition of the trapdoor in respect to the interior of the vestibule;

Fig. 8 is a sectional view taken on the line 8—8 of Fig. 3 through the threshold portion of the trapdoor adjacent to the free edge thereof remote from the hinge and illustrating a resilient member secured to the vestibule platform in the area of the jamb for the side door adapted to cooperate with weatherstripping means on the side door to seal the vestibule at this corner of the trapdoor;

Fig. 9 is a sectional view taken at the hinge edge of the trapdoor on the line 9—9 of Fig. 3 through the threshold portion showing the conditions existing at this point with the threshold member extending beyond the hinge point and the casting member provided for closing the opening in the platform between the end of the threshold member and the end wall and against which the weatherstripping on the vestibule side door is adapted to bear; and

Fig. 10 is a sectional view through one of the hinge bearings, indicated in Fig. 1 as being taken on the line 10—10 and showing the trapdoor in full lines in raised vertical position and in broken lines in lowered horizontal position and clearly revealing the method of attachment of the hinge leaf to the car structure.

In the construction of railway passenger cars having vestibules including platforms having step wells covered by hinged trapdoors capable of being raised to expose the steps, it has been the practice heretofore in the mounting of the trapdoors to construct the trapdoors and platform for separation directly at the hinge, which upon initial installation of the pre-assembled trapdoors necessitated not only extensive fitting operations of the trapdoor itself in the step well opening but required the exercise of the utmost care in the construction of the platform and proportioning of the trapdoor opening to insure proper relationship between the interfitting surfaces of the trapdoor and opening, but most frequently, in spite of all precautions taken in preparation for application of the door to provide for its ready mounting and accurate fit, it has been necessary when applying the trapdoor to resort to elaborate fitting operations involving the chipping and adjustment of the parts to accommodate the trapdoor within the step well opening.

In the present invention all of the foregoing difficulties are obviated and the installation of the trapdoor reduced to a simple procedure by the incorporation of the trapdoor mounting hinge as a part of the prefabricated trapdoor sub-assembly whereby to eliminate the hinge bracket castings at the end wall of the car as heretofore used and permitting the ready application of the trapdoor merely by placement of the sub-assembly within the nosing about the upper step well opening and attaching the hinge butt to the car structure by machine screws.

In the drawings 10 represents a railway car including side walls 11 and having a vestibule 12 defined by body end wall 13 and vestibule end wall 14 and extending full width of the car between side doors 15. A platform 16 in the end zone of the car provides a floor for the vestibule and it is with this platform that the trapdoor of this invention is adapted to be associated. The side wall 11 adjacent the lower area thereof is provided with a depending inwardly curved skirt portion 17, as best shown in Figs. 1 and 2, and in this area, beneath the level of the platform in the zone of the vestibule, a step well 18 is incorporated affording access through the entrance of the car to the platform level from the general station platform level.

Beneath the step well opening in the platform 16, the step well 18 is defined by front and rear side wall closing sheets 19 and 20—see Figs. 1, 2 and 4, and at the inner side by an upper step riser 21 and a fixed step 22 including a riser 23. A folding step assembly 25 is pivotally mounted in the step well by means of adjustable pivot mounting assemblies 24 disposed at respectively opposite sides thereof. The step assembly comprises a plurality of treads 26 and risers 27 extending between supporting side walls 28 and is provided with a bottom cover 29, which, when the steps are inoperatively disposed in closed position conforms to the contour of the inwardly curved skirt portion 17 of the side wall to provide a flush outside surface. At the respectively opposite edges of the step assembly, the step well is provided with flexible closing strips 30 which seal the spaces between the sides of the step assembly and the step well at the side of the car to present a substantially smooth finish when the steps are closed. The step assembly is adapted to fulcrum about the pivots 24 from the closed inoperative position with the bottom

cover flush with the car side to the operative position illustrated in Figs. 1 and 2 where the folding steps 25 complement the fixed step 22 to provide a continuous stairway leading to the vestibule platform 16.

The step well at the platform level is provided with nosing strips 31 and 32 secured along the inner and forward edges of the step well opening for cooperation with the trapdoor of this invention which is adapted to cover the step well to provide a continuous platform surface full width of the vestibule, disposed flush with the level of platform 16. At the rear edge of the step well opening a supporting angle member 33 is secured through the end wall 13 to body end sill 34, and it is to this member that the trapdoor is hinged mounted. The angle member 33 is rigid with the car structure and is disposed with its vertical flange depending and which is secured to the end sill, and its other flange horizontal at a level to support the trapdoor flush with the platform. On the under side of the horizontal flange a smaller angle member 35 is secured, as best shown in Figs. 2, 4 and 10, by means of rivets 36, countersunk on the upper side, with the depending flange disposed outwardly toward the step well in position for attachment of the step well side wall 20 which is secured thereto by self-tapping screws 37. The horizontal flange of the angle member 33 extends across the full depth of the step well from the nosing 31 to the side wall of the car, but is provided with a cutout portion 38 for a purpose hereinafter to appear.

The trapdoor 40 is hinged at that side of the step well defined by the supporting angle 33 and is adapted for coincidental operation with the folding step assembly 25 so that as the trapdoor is raised to inoperative position the steps are automatically lowered to operative position, and when the trapdoor is lowered to a position flush with the surface of the platform 16, the steps are raised to an inoperative position in which the enclosed bottom side 29 is disposed flush with the car side to the same curvature as the contour of the inwardly curved skirt portion 17. This simultaneous cooperative functioning of the trapdoor and steps is effected by means of an adjustable strut 41 connected between the two, as best indicated in Fig. 1, and disposed to the proper side of the pivotal axes of the respective members to accomplish the desired sequence of operations, with the steps lowering as the trapdoor is raised and raising as the trapdoor is lowered. The strut is pivotally connected to a member 42 threaded into the side wall 28 of the step assembly whereby to provide for relative universal movement and adjustment of the strut with respect to the steps. A similar threaded connection 43 is provided to the trapdoor, but this member is threaded into a sliding block 44 mounted in a frame 45 in the trapdoor and adjusted by means of oppositely projectable stud bolts 46 to provide adjustment of the strut in a direction lengthwise of the trapdoor at right angles to the hinge axis. The whole assembly is secured in the trapdoor by the attachment of cover plate 47.

The trapdoor is constructed of top and bottom plates 48 and 49 spaced apart and reinforced by flanged channel stiffening members 51 extending lengthwise of the door between the hinged and free edges at spaced intervals. A flat plate 52 is disposed between each of the members 51 and the top plate 48. At the two edges of the trapdoor, adapted to cooperate with the nosing strips

31 and 32, the bottom plate 49 is formed with a W-shaped section, as at 53 and 54, to provide a continuous recess about these portions of the trapdoor for the reception of weatherstripping 55 which is adapted to be compressed between the W-section and a lower sealing flange 56 on the nosing members effectively to seal these edges of the trapdoor against the entrance of weather from the step well. The weatherstripping 55 is continuous about these two edges of the trapdoor and the hinge edge and is secured in place on the trapdoor by means of clamping strip 57 attached to the bottom wall 48 by screws. At the hinge edge of the trapdoor the bottom wall is not W-shaped as at the other sides adjoining the platform, but is offset as at 58 to provide a continuous recess for the reception of the weatherstripping.

The outside edge of the trapdoor comprises a threshold member 60 having a lower horizontal flange 59 to which the bottom plate 49 is secured, and an upper threshold portion 61 secured to the upper plate 48. Adjacent the innermost portion of the threshold a channel member 62 is disposed between the upper and lower plates to reinforce the trapdoor at this point and in effect produce a box section threshold construction. A depending flange 63 on the threshold overlies the outer face 29 of the step assembly in the closed position and closes the gap which otherwise might exist between the parts. A raised abutment 64 on the upper surface of the threshold member is adapted to cooperate with a weatherstrip 65 on the vestibule side door 15 to seal the vestibule at this point. The threshold extends from the free edge of the trapdoor to a point beyond the hinge axis, as best shown in Fig. 3, and is cut out adjacent the free edge of the trapdoor to fit around door jamb 66, and in order to provide a proper weatherstripping condition at this corner of the platform a rubber block 67 is mounted in position and shaped to be engaged not only by the cut out portion of the threshold but by the weatherstrip 65 on the bottom of the side door 15 and by the weatherstrip 63 on the side of the door adapted to engage the jamb 66. On the underside of the threshold, non-metallic bumpers 69 are provided to prevent metal to metal contact between the folding steps and trapdoor in the closed position. A fabricated metal pocket 71, adapted to receive the adjustment mechanism for the connecting strut 41, is secured in the trapdoor between the reinforcing members 51. The upper surface of the trapdoor is covered with non-metallic material 72 which may be linoleum or rubber tile or, if desired, metal having a non-skid tread surface might be utilized for the purpose. Metal edge binding 73 arranged flush with the threshold surface 61 is disposed about the three sides of the trapdoor other than the threshold.

The hinge structure for the trapdoor, which is adapted to be incorporated as a part of the trapdoor construction for application to the car as an integral part thereof upon installation of the assembly in the step well opening, includes a tubular member 74, rigid with the trapdoor. The member 74 is mounted to the trapdoor by means of an enveloping rebent plate member 75 enclosing the tubular member and integrally secured in the rear edge construction of the trapdoor. As best shown in Fig. 4, the plate 75 encircles the tubular member 74 and is provided with return flanges 76 entered between the trapdoor top plate 48 and the offset portion 58 of the bottom plate 49, with a filler block 77 disposed therebetween to provide a rigid edge structure with the tubular

construction actually forming the rear edge of the trapdoor.

The tubular member 74 comprises the hinge axis of the trapdoor and extends continuously between hinge butts 78 which support pintles 79 about which the trapdoor is adapted to pivot during operation, and which are fixed in the hinge butts by means of set screws 81 and project into the opposite ends of tubular member 74. The hinge butts are integrally secured to a substantially Z-shaped hinge leaf plate 80 extending continuously full length of the hinge edge of the trapdoor from the inner side of the threshold 60 to the nosing 31 on the edge of the platform opening at the step well. The plate 80 is provided with an upper attaching flange 82 and a lower sealing flange 83, with an arcuate connecting portion 84 curved about the tubular member 75 and the hinge butts 78. The hinge butts are spaced apart in axial alignment to receive the tubular structure 75 therebetween and are disposed at opposite ends of the plate 80 to which they are secured by welding 85 in the curved portion 84, as best shown in Fig. 10.

The lower flange 83 of the plate 80 is disposed on a level with the sealing flange 56 on the nosing strip at the edge of the step well opening, and, like that member, cooperates with the weatherstrip 55 to seal the opening against the passage of weather from the step well into the vestibule when the trapdoor is closed, as best shown in Fig. 4. The upper flange 82 comprises the attaching means for securing the trapdoor to the car structure and is removably secured to the horizontally extending flange of the supporting angle 33 by means of machine bolts 86 having countersunk heads on the upper surface. The attaching leaf 82 is covered by a finish strip 87 extending from the end wall 13 to the hinge tubular portions 40 and completely concealing the hinge leaf from the threshold to the platform, and which is secured by the same bolts attaching the hinge leaf to the angle 33. It will be seen that once the hinge pintles 79 are entered through the hinge butts 78 into the opposite ends of tubular member 74 to provide trunnions about which the trapdoor pivots, the hinge leaf 80 operatively becomes a unitary part of the trapdoor and is thus pre-assembled with the trapdoor before installation on the car. The sub-assembly is applied to the platform while the car is under construction, and in making the application to the car, the trapdoor with the attached hinge structure is brought to the erection location and placed in the step well opening in proper relation to the nosing strips 31 and 32 along the inner and forward edges, and the hinge leaf 82 is then drilled, together with the supporting angle member 33, for the reception of securing bolts 86 which are then installed to secure the assembly.

The threshold 60 on the trapdoor, as stated, extends beyond the hinge axis, and the hinge structure extends from the inner side of the projecting portion of the threshold to the inner edge 65 of the trapdoor. A sealing block 88, of rubber, is disposed between the end of the hinge structure and the threshold, and as best shown in Fig. 6, is fitted into the hinge butt 78 and secured to the hinge pintle 79 by means of a screw 89 in position to be wiped by the threshold during opening and closing operations of the trapdoor, and a depending lip 91 on the threshold insures full engagement with the rubber blocks at all times. The projecting portion of the threshold during operation of the trapdoor passes through the planes

of the step well side wall 20 and the horizontal flange of the supporting angle 33 which are cut away to provide for this passage. The opening thus resulting in the platform at this point is closed by means of a filler block 92 secured by screws 93 to the supporting angle, with an underlying strip of rubber 94 therebetween and extending beyond the horizontal flange of the supporting angle in position to be contacted by a projecting lip 95 on the threshold (see Fig. 10) to provide a complete seal about the joint against the entrance of weather into the vestibule from the step well. The opening in the side wall 20 of the step well is closed by a pressed plate 96 curved to the radius of the arc described by the projecting portion of the threshold and secured to the side wall 20 and the horizontal flange of the supporting angle by means of screws 91.

The trapdoor is releasably secured in the closed position at the platform level by means of a combination lock and kick-up device 98 which automatically engages the trapdoor when it is lowered and may be manipulated by the foot when it is desired to release the trapdoor. In the raised position, the trapdoor is secured against the outer face of the vestibule side door 15 by means of a manually releasable securing device 99 which is automatically engaged when the trapdoor is raised and which engages the same device on the trapdoor for holding it open as is engaged by the catch 98 for holding it closed. It will be noted that the vestibule side door is hinged at 39 to the vestibule end wall 13 and overlies the trapdoor in the closed position whereby to provide the safety feature that the side door must be opened fully before the trapdoor can be raised, and in the open position swings completely clear of the trapdoor area against the end wall to permit full opening of the trapdoor.

From the foregoing it will be seen that there has been provided a railway car trapdoor having an integrated pre-assembled hinge structure which may be brought to the car as a sub-assembled unit and readily installed over the step well opening in the platform merely by attaching the hinge to the platform structure, and which provides for the complete weather-stripping of the joints thereabout to prevent the entrance of weather into the vestibule from the step well.

What is claimed is:

1. A railway car platform and trapdoor construction including a step well and comprising a car vestibule having a step well opening in the platform at one side of the car, nosing strips about two sides of said opening, a trapdoor supporting member forming part of the car structure at the hinge side of the opening and disposed immediately beneath the level of said platform, a hinged trapdoor for covering said step well having a continuous weatherstrip adapted to cooperate with said nosing to seal the step well opening along said two sides, a hinge for the trapdoor forming a pre-assembled part of the trapdoor structure having a leaf portion secured to said supporting member, said hinge comprising a butt plate including said leaf portion and an offset sealing flange connected by a bent plate portion, axially aligned hinge butts spaced apart and integrally secured to the butt plate in said offset bent plate portion, a continuous tubular hinge axis member secured to the trapdoor and nested between said butt members, and removable pintle members engageable between said hinge butts and the tubular axis member about which the trap-

door is adapted to pivot, said sealing flange cooperating with said continuous weatherstrip to seal the step well opening at the hinge edge of the trapdoor, and means overlying said leaf portion on the supporting member substantially flush with said platform.

2. A railway car platform and trap-door construction including a step well and comprising a car vestibule having a step well opening in the platform at one side of the car, nosing strips about two sides of said opening, a trapdoor supporting member forming part of the car structure at the hinge side of the opening, a hinged trapdoor for covering said step well having a continuous weatherstrip adapted to cooperate with said nosing to seal the step well opening along said two sides, a hinge for the trapdoor forming a pre-assembled part of the trapdoor structure having a leaf portion secured to said supporting member, said hinge comprising a butt plate including said leaf portion and an offset sealing flange extending beneath the hinge, axially aligned hinge butts spaced apart and integrally secured to the butt plate, a continuous tubular hinge axis member secured to the trapdoor and nested between said butt members, and pintle members engageable between said hinge butts and the tubular axis member about which the trapdoor is adapted to pivot, said sealing flange cooperating with said continuous weatherstrip to seal the step well opening at the hinge edge of the trapdoor.

3. A railway car platform and trapdoor construction including a step well and comprising a car vestibule having a step well opening in the platform at one side of the car, a trapdoor supporting member forming part of the car structure at the hinge side of the opening, a hinged trapdoor for covering said step well having a continuous weatherstrip adapted to seal the step well opening, a hinge for the trapdoor forming a pre-assembled part of the trapdoor structure having a leaf portion secured to said supporting member, said hinge comprising a butt plate including said leaf portion and sealing flange extending beneath the hinge, axially aligned hinge butts spaced apart and secured to the butt plate, a tubular hinge axis member on the trapdoor nested between said butt members, and pintle members engageable between said hinge butts and the tubular axis member about which the trapdoor is adapted to pivot, said sealing flange cooperating with said continuous weatherstrip to seal the step well opening at the hinge edge of the trapdoor.

4. A railway car platform and trapdoor construction including a step well and comprising a car vestibule having a step well opening in the platform at one side of the car, a hinged trapdoor for covering said step well having a bottom weatherstrip adapted to seal the step well opening, a trapdoor supporting member at the hinge side of the opening, a hinge for the trapdoor having a leaf portion secured to said supporting member, said leaf portion including a sealing flange extending beneath the hinge for cooperation with said weatherstrip to seal the step well opening at the hinge edge of the trapdoor, axially aligned hinge butts forming part of the hinge and disposed between said leaf portion and said sealing flange, a tubular hinge member on the trapdoor extending between said butt members, and a pintle member engageable between said hinge member on the trapdoor and said hinge butts and about which the trapdoor is adapted to pivot.

5. A trapdoor for a railway car vestibule step well opening including an integrated trapdoor and hinge construction, said hinge comprising a butt plate including an attaching leaf portion, a sealing flange beneath the hinge, axially aligned hinge butts spaced apart on said butt plate, a hinge member on the trap-door forming the connection between the trapdoor and hinge construction, and a pintle member forming a pivotal connection between said hinge member and the hinge butts, said trapdoor having a bottom weatherstrip cooperating with said sealing flange to seal the hinge construction against the passage of weather.

6. A trapdoor for a railway car vestibule step well opening having an attached hinge construction, said hinge comprising a butt plate including an attaching leaf portion and an offset sealing flange extending beneath the hinge, axially aligned hinge butts on said butt plate at said offset substantially between the planes of said leaf portion and said sealing flange, a tubular hinge member on the trapdoor extending continuously between said hinge butts, and separate pintle members fixed in the respective butt members and extending into said tubular hinge member and about which the trapdoor is adapted to pivot, said trapdoor having a bottom weatherstrip cooperating with said sealing flange to seal the hinge construction against the passage of weather.

7. A railway car trapdoor comprising a sub-assembly having a preassembled hinge structure integrated therewith for installation as a unit in the step well opening of a railway car platform and including a hinge butt plate having an attaching leaf portion and a flange extending beneath the hinge, a pair of axially aligned hinge butts on said flange, hinge means on the trapdoor in axial alignment with and extending continuously between the hinge butts, and pivot means engageable between said hinge means and hinge butts to provide a pivoted connection for the trapdoor.

8. A railway car trapdoor hinge comprising a butt plate having upper and lower flanges, one of said flanges comprising an outwardly extending attaching flange and the other extending beneath the hinge axis, an intermediate arcuate portion connecting said flanges, a pair of hinge butts spaced apart on said butt plate, a complemental hinge member continuous between said hinge butts, means for securing said member to a trapdoor, and pivot means engageable between said hinge member and the hinge butts, the axes of said hinge member, hinge butts and arcuate portion being substantially coincident.

9. A railway car platform and trapdoor construction including a step well and comprising a car vestibule having a step well opening in the platform at one side of the car, a hinged trapdoor for covering said step well having a bottom weatherstrip adapted to seal the step well opening, a trapdoor supporting member at the hinge side of the opening, a hinge structure for the trapdoor having an attaching leaf portion secured to said supporting member and including a bottom flange extending beneath the hinge for cooperation with said weatherstrip to seal the step well opening at the hinge edge of the trapdoor, axially aligned hinge butts on said flange, a complemental hinge member on the trap-door disposed between said hinge butts, hinge pintle means engageable between said hinge member and the hinge butts about which the trapdoor

is adapted to pivot, said trapdoor having a threshold at that side adjacent the side of the car extending full length of the trapdoor from the free edge thereof and beyond said hinge structure, means sealing the joint around said threshold beyond the hinge structure, and sealing means between the end of said hinge structure and the threshold.

10. A railway car platform and trapdoor construction including a step well and comprising a car vestibule having a step well opening in the platform at one side of the car, a hinged trapdoor for covering said step well having a bottom weatherstrip adapted to seal the step well opening, a trapdoor supporting member at the hinge side of the opening, a hinge structure for the trapdoor having an attaching leaf portion secured to said supporting member and including a bottom flange extending beneath the hinge for cooperation with said weatherstrip to seal the step well opening at the hinge edge of the trapdoor, axially aligned hinge butts on said flange, a complemental hinge member on the trapdoor disposed between said hinge butts, and hinge pintle means engageable between said hinge member and the hinge butts about which the trapdoor is adapted to pivot, said trapdoor having a threshold at that side adjacent the side of the car extending full length of the trapdoor from the free edge thereof and beyond said hinge structure.

11. A railway car trapdoor comprising a sub-assembly having a preassembled hinge structure integrated therewith for installation as a unit in the step well opening of a railway car platform and including a hinge butt plate having an attaching leaf portion and a pair of axially aligned hinge butts, hinge means on the trapdoor in axial alignment with and continuous between the hinge butts, and pivot means engageable between said hinge means and hinge butts to provide a pivotal connection for the trapdoor.

12. A railway car trapdoor comprising a sub-assembly having a preassembled hinge structure integrated therewith for installation as a unit in the step well opening of a railway car platform and including a hinge butt plate for attachment to said platform, a pair of spaced apart hinge butts on said plate, and continuous hinge means on the trapdoor in axial alignment between said hinge butts and cooperating therewith to provide a pivotal connection for the trapdoor.

13. A railway car trapdoor comprising a sub-assembly having a preassembled hinge structure integrated therewith for installation as a unit in the step well opening of a railway car platform and including a hinge butt plate for attachment to said platform, and a pair of spaced apart hinge butts on said plate, said trapdoor having a continuous tubular edge structure in axial alignment between said hinge butts and pivotally associated therewith to provide a pivotal connection for the trapdoor.

14. A railway car trapdoor comprising a sub-assembly having a preassembled hinge structure integrated therewith for installation as a unit in the step well opening of a railway car platform and including a hinge plate, hinge butts secured to said plate, a hinge member on the trapdoor pivotally connected with said hinge butts, said plate having an outwardly directed upper flange for attachment to said platform and an inwardly directed lower flange extending beneath the hinge, and an arcuate portion connecting said upper and lower flanges, the axes of said hinge

structure and of said arcuate portion being substantially coincident.

15. A railway car trapdoor comprising a sub-assembly having a preassembled hinge structure integrated therewith for installation as a unit in the step well opening of a railway car platform, said hinge structure comprising a tubular hinge member on the trapdoor, a hinge butt operatively connected with the hinge member, a hinge plate supporting said hinge butt having an outwardly directed upper flange for attachment to said platform and an inwardly directed lower flange extending beneath the hinge, and an intermediate portion integrally connecting said flanges.

16. A railway car trapdoor hinge comprising a 15 butt plate including an outwardly directed attaching flange having a depending arcuate portion disposed inwardly, a pair of hinge butts spaced apart on the butt plate, a complemental hinge member continuous between said hinge butts, and pivot means engageable between said hinge member and the hinge butts, the axes of said hinge member, hinge butts and arcuate portion being substantially coincident.

17. A railway car trapdoor hinge comprising 20 a butt plate having an outwardly directed upper attaching flange and an inwardly directed lower flange extending beneath the hinge axis, an inter-

5

10

15

mediate arcuate portion connecting said flanges, a pair of hinge butts spaced apart on the butt plate, and continuous hinge means on the trapdoor pivotally connected between the hinge butts, the axes of said hinge means, hinge butts and arcuate portion being substantially coincident.

18. A railway car trapdoor hinge comprising a hinge butt including an outwardly directed attaching flange and a depending arcuate portion disposed inwardly and supporting a pair of bearings in spaced apart relation, and a complemental hinge member pivotally mounted between said bearings, the axes of said hinge member and of said arcuate portion being substantially coincident.

CHRISTIAN J. BEEZHOLD.
